(57) **CLAIM**

(***) Term: **14 Years**

The ornamental design for a neonatal magnetic resonance scanner, as shown and described.

(21) Appl. No.: **29/473,617**

DESCRIPTION

(22) Filed: **Nov. 25, 2013**

FIG. 1 is a perspective view of a neonatal magnetic resonance scanner incorporating my new design;

(51) **LOC (10) Cl.** **24-01**

FIG. 2 is a front elevation view thereof;

(52) **U.S. Cl.**

FIG. 3 is a back elevation view thereof;

(58) **USPC** **D24/158**

FIG. 4 is a left side elevation view thereof;
